DOOR ATTACHMENT HANGER APPLIANCE

Bonner B. Hauser, St. Paul, Minn.

Application June 24, 1938, Serial No. 215,621

5 Claims. (Cl. 211—86)

My invention relates to an improvement in door attachment hanger appliance wherein it is desired to provide a means of attaching garment, hat and shoe supports to a door without marring the appearance of the door.

Many types of fixtures have been previously provided for the purpose of supporting hats, ties, shoes and the like, and many of these devices are designed to be attached to the inner surface of a closet door or the like. However, in these former devices with which I am familiar, it is necessary to attach the racks or fixtures to the door by means of screws or nails so that if these fixtures are later removed, the nail or screw openings detract from the appearance of the door.

It is a purpose of the present invention to provide a hanger appliance consisting in a series of strips which engage the top edge of the door and also the bottom edge of the same, thus being firmly anchored at both ends thereof. In attaching an appliance of this type, screws or nails are driven into the door, but these screws or nails extend into the top edge of the door and into the bottom edge of the same where the openings are not visible after the appliance has been removed. Thus if my appliance is later removed from the door, the appearance of the door is not affected in any way as the openings in the door which formerly contained the screws holding the appliance in place, are not in position to be visible.

It is a feature of my invention to provide a construction including a pair of parallel bars extending vertically over the surface of a door which may be used to support any desired combination of garment supporting devices. For example, in preferred form, a hat and tie support is mounted, overlying the upper portion of a door and a shoe support is mounted overlying the lower portion of the door. If on the other hand, it was desired to provide a support for coats or the like, near the top of the door, it would perhaps be advisable to reduce the size of the shoe supporting device or to eliminate this portion of the device entirely. My apparatus is flexible and may be used for the support of various types of garment supporting devices.

It is a purpose of my invention to provide a hanger appliance which may be secured to a door regardless of the size of the same. A means is provided of adjusting the length of the appliance so that one standard form of appliance may be used for various sizes of doors, thereby elimi-

nating the necessity of making a different size appliance for each size of door.

It is a feature of my invention to provide a door attachment hanger appliance which supports various appliances at a point slightly spaced from the surface of the door so that any relative movement between the appliance and the door will not act to scratch or otherwise mar the surface of the door. My appliance is slightly offset from the inner door surface and holds the garment supporting devices spaced slightly from the door. It is also possible to provide a bumper device which is formed of soft rubber or the like, and which engages the surface of the door to the rear of the appliance, so as to hold the appliance properly spaced from the door between the ends of the appliance.

These and other objects and novel features of my invention will be more clearly and fully set forth in the following specification and claims.

In the drawing forming a part of my specification:

Figure 1 is a perspective view of a closet door illustrating my appliance attached thereto.

Figure 2 is a perspective view in enlarged form of my hanger appliance, showing a portion thereof broken away to permit the important parts thereof to be properly illustrated.

Figure 3 is a perspective view of the central portion of my appliance, the portions forming the same being spaced apart to illustrate the arrangement of openings and slots therein.

Figure 4 is a cross-sectional view through the connecting joint between the two main portions forming the appliance.

Figure 5 is a cross-sectional view through a slightly different form of construction, the section being shown at the joint where the two relatively telescopic members connect.

40 My door attachment hanger appliance A is designed for attachment to a closet door B. This attachment is connected to the door B as best illustrated in Figure 2 of the drawing. The hanger A includes a pair of vertically extending supporting telescopic members 11 and 12. The upper member 11 is provided with a horizontally extending flange 13 having openings therethrough through which screws 14 may

45 extend to secure the upper portion of the hanger bar to the door B, the screws 14 extending into the edge 15 of the door B where these screws are concealed by being countersunk. Obviously even though the screws 14 were removed and the hanger A detached, the screw holes remaining

in the edge 15 would not be visible because of the position of the same.

The portion 11 is provided with a downwardly extending flange 16 adjacent the attachment flange 13 and an inclined portion 17 which connects the flange 16 with the main body 19 of the strip 11. The main body 19 is provided with rearwardly extending flanges 20 on each of the opposite edges thereof so that the main body portion 19 of the strip 11 is channel-shaped, thus giving rigidity to the body.

An opening 21 extends through the strip 11 near the bottom end of the strip and slightly above this opening 21 is an elongated slot or aperture 22. These apertures 21 and 22 co-operate with other apertures in the strip 12 in a manner which will be later described.

The strip 12 includes an attaching flange 23 having openings therethrough through which screws 24 may extend to secure the flange 23 to the bottom edge 25 of the door B. From the flange 23 the strip 12 inclines outwardly as illustrated at 26 to space the strip 12 from the surface of the door and the inclined portion 26 connects with the main body portion 27 of the strip. Oppositely disposed flanges 29 form the body 12 into channel shape and act to stiffen the strip 12.

The strip 12 is slightly narrower than the strip 11 and the flanges 29 thereupon engage between the flanges 20 on the strip 11. Thus the strips 11 and 12 are longitudinally adjustable with respect to one another. An opening 30 is provided in the strip 12 near the top end thereof, and an elongated aperture or slot 31 extends centrally through the strip 12 at a point spaced from the aperture 30.

In attaching the strips 11 and 12 together, one bolt 32 or other similar attaching means extends through the aperture 22 and through the aperture 30 in the strip 12. The bolt is held in rigid position with respect to the strip 12, but the strip 11 is permitted to slide with respect thereto throughout the length of the slot 22. A second bolt 33 or other suitable attaching means extends through the opening 21 and the elongated aperture 31. This bolt is held in fixed relation to the strip 11 but is slidably adjustable throughout the length of the slot 31. Therefore, when the bolts 32 and 33 are slightly loose the strips 11 and 12 may relatively longitudinally move throughout the length of the slots 22 and 31. To the vertical strips 10 may be attached any desired hanger device.

In the form illustrated in Figure 1 of the drawing, a rectangular metallic frame 34 is attached to the vertical strips 10 by means of bolts 35. To the rectangular frame 34 is attached a series of hat supporting brackets 36 and also a tie supporting rack 37. Thus a series of hats and a large number of ties may be supported on the inner surface of the closet door. Similarly, a rectangular frame 39 may be attached by bolts 40 to the vertically extending strips 10 and shoe supporting rods 41 may be supported by suitable brackets 42 attached to the frame 39. The manner in which hats, ties, and shoes may be supported upon the strips 10 is illustrated in this Figure 1 of the drawing.

Figures 4 and 5 illustrate slightly different forms of construction of the strip portions 11 and 12 of the strips 10. In Figure 4 of the drawing, I illustrate a bolt 43 having a head 44 carrying an enlarged soft rubber bumper member 45. The bolt 43 is provided with a nut 46 on the

inside of the strips 11 and 12 and with a cap nut 47 on the outside of these strips. The nut 46 may be used to vary the depth between the bumper 45 and the strips 11 and 12, whereas, 5 the nut 47 holds the strips 11 and 12 clamped together.

In Figure 5 of the drawing, I illustrate channels slightly different in form from those illustrated in the remaining views. In this form, the 10 lower strip portion 12' is identical with that previously described. The upper strip 11', however, is provided with rolled or arcuated edges 49, overlying the flanges 29' of the inner strip 12'. The construction is otherwise identical to that 15 illustrated in views 1, 2 and 3 of the drawing.

The manner in which my appliance may be used is believed obvious from the foregoing description. The strips 10 may be attached to a 20 door of any size, these strips being longitudinally adjustable to compensate for a variance in the length of the door. When the strips 10 have been attached, obviously the garment supporting devices may be attached to the strip and these devices may be of any desired form. When the 25 strips 10 are removed from the door, the only screw holes in the door will be positioned in the top and bottom edges of the door where they will not be visible and accordingly my hanger appliance may be attached and removed without affecting the appearance of the door in any way whatsoever.

In accordance with the patent statutes I have described the principles of construction and operation of my door attachment hanger appliance, and while I have endeavored to set forth the best embodiments thereof, I desire to have it understood that this is only illustrative of a means of carrying out my invention and that obvious changes may be made within the scope 35 of the following claims without departing from the spirit of my invention.

I claim:

1. A door attachment hanger appliance comprising a body portion including a pair of telescopically adjustable members, attaching means for the ends of said body, said adjustable members having offset portions, bumper means holding the offset portion of said body in spaced relation from the plane of the non-offset portions thereof, and means supporting said bumper means and engaging said relatively adjustable telescopic members and holding the same in adjusted position.

2. A door attachment hanger appliance comprising a pair of telescopically adjustable members, one comprising an end flange designed to overlie a door edge, a bearing portion at substantially right angles to said end flange, and connected at one end thereto, designed to overlie a portion of the door surface adjacent the edge, an outwardly and downwardly inclined connecting portion on the other end of said bearing portion, and a body portion parallel to said bearing portion; the other of said members comprising an end flange designed to overlie a door edge parallel said first mentioned door edge, an outwardly and upwardly inclined connecting portion connected to said end flange, and a body portion connected to said last named connecting portion and at substantially right angles to said end flange, and means securing said body portions together in adjusted position.

3. A door attachment hanger appliance comprising a pair of telescopically adjustable members, one comprising an end flange designed to

overlie a door edge, a bearing portion at substantially right angles to said end flange designed to overlie a portion of the door surface adjacent the edge, an inclined connecting portion on said bearing portion, and a body portion parallel to said bearing portion; the other of said members comprising an end flange designed to overlie a door edge parallel to said first mentioned door edge, an inclined connecting portion connected to said end flange, and a body portion connected to said last named connecting portion and at substantially right angles to said end flange, each said body including a longitudinally extending slot and a smaller aperture, said smaller aperture in each of said members corresponding with the slot in the other of said members, and bolts through said corresponding apertures and slots to secure said members in adjusted position.

4. A door attachment hanger appliance adapted for attachment to a door, comprising a pair of telescopically adjustable strips connected together, each strip having a free end, a portion near the free end of one of said strips

designed to contact and overlie the surface of a door, a flange on the free end of each of said strips, means for attaching said flanges to opposed edges of the door, connecting portions connected to said surface contacting portion of said one strip and the flange on the other of said strips, respectively, the strips between said connecting portions extending in spaced parallel relation to said door surface.

5. A door attachment adapted for attachment to a door, comprising a pair of substantially parallel rack supports, each support comprising a pair of telescopically adjustable members designed to extend parallel to a surface of the door, a pair of end flanges on opposite ends of said members arranged in horizontal parallel relationship, means for securing said end flanges to the top and bottom edges of said door, means securing said members in adjusted relationship, and a series of rack means connecting said parallel rack supports.

BONNER B. HAUSER.
